UNITED STATES PATENT OFFICE.

JAMES G. GREENE, OF ELIZABETH, NEW JERSEY, ASSIGNOR TO THE SINGER
MANUFACTURING COMPANY OF NEW JERSEY.

CUTTING MECHANISM FOR BUTTON-HOLE SEWING-MACHINES.

SPECIFICATION forming part of Letters Patent No. 351,760, dated November 2, 1886.

Application filed April 2, 1886. Serial No. 197,508. (No model.)

To all whom it may concern:

Be it known that I, JAMES G. GREENE, a citizen of the United States, residing at Elizabeth, in the county of Union and State of New Jersey, have invented certain new and useful Improvements in Cutting Mechanism for Button-Hole Sewing-Machines, of which the following is a specification, reference being had therein to the accompanying drawings.

10 My invention relates to certain improvements in the cutting mechanism for button-hole sewing-machines described in Patent No. 322,428, dated July 21, 1885, the object of my invention being to relieve the bed-plate of the machine of the shock or jar of the striking button-hole cutter or cutting-lever. To this end I provide beneath the bed-plate of the machine a sustaining-block, which extends under the forward end of the rock-shaft by which the 20 cutting mechanism is operated, so that the said shaft may be supported by the said sustaining-block when the cutting-blow is given, thus transferring the force of the blow to the said block, and thereby relieving the bed-plate from 25 the shock thereof.

In the drawings, Figures 1 and 2 are side views, partly in section, of sufficient of a button-hole sewing-machine to illustrate my invention, the parts being in different positions 30 in the two views. Fig. 3 is a detail end view, the parts therein shown being in the same position as in Fig. 1, and Fig. 4 is a view similar to Fig. 3, but with the parts in the position indicated by Fig. 2. Fig. 5 is an end view of the bed-plate, partly in section; and Figs. 6, 35 7, and 8 are views similar to Figs. 2, 3, and 4, respectively, illustrating a modified form of my invention.

A denotes the bed-plate, and B a portion of 40 the arm of a button-hole sewing-machine.

C is a rock-shaft supported by center-screws passing through hangers a, depending from the bed-plate A, said shaft being connected by a link, d, with a striking cutting-lever, D, having at its forward end a weighted head carrying a cutting-block, d'. The shaft C is provided at its rear end with an operating-handle, e, and at its forward end with a cam, c'.

Pivoted to ears a' on the bed-plate A is an 45 arm or lever, G, which rests on the cam c',

and to the said arm or lever is attached the button-hole cutter g.

The mechanism thus far described is the same as in Patent No. 322,428, above referred to, excepting that the cutter is in the present 55 instance below the bed-plate and the cutting-block above, and by moving the handle c quickly upward from the position indicated in Fig. 3 to the position indicated in Fig. 4 the cutting mechanism will be operated in the same 60 manner as in the machine described in the said patent.

To relieve the bed-plate of the shock of the blows of the cutting-lever, and thus prevent the mechanism carried by the said plate from 65 being disarranged or otherwise injured by such shock, I provide a sustaining-block, F, which is arranged beneath the lifting-cam c' on the rock-shaft C, or, in other words, beneath the forward end of the said shaft. The bed-plate 70 A is hinged at its rear side to standards secured to the table E, and I prefer to support the front side of said bed plate by a post, f, also secured by said table. In the present instance the standards F' f', respectively, are 75 formed integral with the base-pieces f' f' of the said sustaining-block and post. The standard f' is not clearly shown, except in Fig. 6, (from which the post f is omitted;) but it will be understood that it is or may be of the same 80 form as the standard F', (clearly shown in Fig. 5.)

On the shaft C is a small cam, c', which may be merely an extension of the cam c'. When the handle c is lifted in the operation of cutting a button-hole, the cam c', impinging against the sustaining-block F, (or a cushion or plate, f', thereon,) lifts the bed-plate A slightly from the post f, (see Fig. 2,) and the force of the blow of the cutting-lever D will 90 thus be communicated to the said block F, thereby relieving the bed-plate from the shock of the blow.

The lifting of the bed-plate by the cam c' on the shaft C is due to the fact that the said shaft is rigidly connected with the said bed-plate through the hangers a, by which it is supported, so that as the said shaft is turned in the operation of cutting a button-hole the impingement of the said cam against the block F (or its cushion 95 f') will lift the bed-plate A from the post f, thereby relieving the bed-plate from the shock of the blow.

ion f^3) forces the said shaft upward, and thus slightly lifts the front side of the bed-plate from the post f , as above stated.

Instead of supporting the front side of the bed-plate by the post f , as above described, said post, and also the cam c^4 , may be omitted, and the forward end of the shaft C may rest directly on the block F , which will thus serve as a support for the front side of the bed-plate, both when the button-hole is being cut and at other times. (See Figs. 6, 7, and 8.) I prefer, however, to employ the post f and cam c^4 , as hereinbefore described, as with this construction there will be less friction on the shaft C at the beginning of the movement of the latter in cutting; but I do not wish to be understood as limiting my invention to this my preferred construction.

It will be obvious that, instead of arranging the cutter g below the bed-plate and the cutting-block d' above the same, the positions of these two parts may be the same as in the patent hereinbefore referred to, on which my invention is an improvement.

Having thus described my invention, I claim and desire to secure by Letters Patent—

1. In a button-hole sewing-machine, the

combination, with the bed-plate thereof, a striking cutter-lever, a cutting-block, a cutter, and a rock-shaft by which the said cutter and block are operated, and which is connected with the said bed-plate, of a sustaining-block below the said bed-plate and beneath the forward end of the said rock-shaft, whereby when the said cutter is operated the force of the blow will be communicated to the said sustaining-block and the bed-plate relieved of the shock, as set forth.

2. In a button-hole sewing-machine, the combination, with the hinged bed-plate, a post for supporting the front side thereof, a striking cutter-lever, a cutting-block, a cutter, and a rock-shaft for operating said cutter and block, of a sustaining-block beneath the said bed-plate, and a cam on said rock-shaft adapted to impinge against said sustaining-block to lift the front side of the bed-plate from the said post when the cutter is operated, substantially as and for the purpose set forth.

In testimony whereof I affix my signature in presence of two witnesses.

JAMES G. GREENE.
